UNITED STATES PATENT OFFICE.

FRANK ALDRICH, OF DETROIT, MICHIGAN, ASSIGNOR OF FOUR-FIFTHS TO
ISAAC N. ALDRICH AND JAS. P. MAIN, OF SAME PLACE.

CAR SEAL AND TAG.

SPECIFICATION forming part of Letters Patent No. 535,043, dated March 5, 1895.

Application filed December 20, 1894. Serial No. 532,418. (No model.)

To all whom it may concern:

Be it known that I, FRANK ALDRICH, a citizen of the United States, residing at Detroit, in the county of Wayne and State of Michigan, have invented certain new and useful Improvements in Railway-Car Seals and Tags; and I do hereby declare the following to be a full, clear, and exact description of the invention, such as will enable others skilled in the art to which it appertains to make and use the same, reference being had to the accompanying drawings, which form part of this specification.

My invention relates to railway car seals and tags, and has for its object to provide a simple and cheap device for the purpose that can be quickly and easily locked upon the car, and when thus secured cannot be removed either by accident or design except by cutting or breaking it off from its position on the car doors, and to this end my invention consists in the several details of construction of the seal and tag, and in the peculiar manner of locking it in position on the car as hereinafter described and more particularly pointed out in the claims.

Referring to the drawings: Figure 1 represents a plan view of the blank from which the seal and tag are formed. Fig. 2, is a similar view with the lips of the seal bent over to form a loop for the reception of the tongue of the seal. Fig. 3, is an edge view, partly in section, showing the seal in position on the car, and the end of the tongue in the loop. Fig. 4, is an edge view showing the end of the tongue locked into position. Fig. 5, is a sectional view of the upper portion of the seal shown in Fig. 4. Fig. 6, shows a slightly modified form of my seal and tag; and Fig. 7, represents the male and female dies, the latter in section, of pliers employed to upset the metal of the joined ends of the seal and lock them together.

Similar letters of reference indicate corresponding parts in each figure of the drawings.

The blank A consists of a strip stamped or cut out of any desired kind of suitable metal to form the seal portion a, and D, and the tag portion B integral with each other. The loop blank D is adjacent to the tag B, and between

the tag and the tongue a, of the seal and is wider than the tongue as shown in Figs. 1 and 6, and between the loop and the tag blank there is a short cross slit c, on each side for the purpose of enabling the lips d, to be turned over upon the body of the blank to form the loop having the groove or recess b, for the reception of the free end of the tongue a, of the seal as shown in Fig. 2.

In Fig. 6, I have shown a slightly modified form of my blank for the seal and tag in which the strip is stamped out of the metal so as to form a bulge in width in its longitudinal center to receive the number of the tag to be placed thereon, and there is a loop d, adjacent thereto at one end, and the tongue a, of the seal extending from the other end. In this form of tag and seal, the tongue is inserted in the outer end of the loop d, the same as in the form shown in Fig. 2, leaving the tag B to form a portion of the band which is passed through the staples of the car, and which is out of the way and does not form a projection or flap extending from the seal, which is more unsightly and sometimes in the way, and this form is preferable for use in most instances on this account.

It has been found a great advantage to make the tags B integral with the seals, as the separate manufacture of the tags is thereby avoided, and the tags are always at hand when it is desired to use the seal, without the additional care of securing a detached tag to the seal. These tags have consecutive numbers painted thereon or stamped into the metal by means of a die, and are always ready for use in their numerical order. In the form of blank shown in Fig. 2, the numbers are placed upon the tag on the same side of the blank on which the loop d, is formed; but in the form of blank shown in Fig. 6, the numbers are placed on the tag on the opposite side of the blank from the loop in which the tongue a, of the seal is inserted.

C represents the staples on the car in which the seal is secured. The free end of the tongue a, of the seal is preferably somewhat tapered in order that it may be readily inserted in the recess b, of the loop.

E and F represent respectively the male and female dies of a pair of bending and punch-

ing pliers. On the under side of the male die E there is a conical punch *e*, formed, which is adapted to enter a perforation *f*, in the bottom of the female die F. The handles of these 5 pliers, which are not shown, may be pivoted together and are of any ordinary kind in common use.

In applying the seal the free end or tongue *a*, is passed through the staples C of the car 10 and the end of the tongue inserted in the recess *b*, of the loop and at its most distant end from the tongue. It is then pushed through to the opposite end of the loop as shown in Fig. 3. The joint is then placed between the 15 dies E and F of the pliers, when on applying the pressure and forcing the dies together, the joint portion of the seal will be bent into a **U** shape and a conical hole will be punched through the several thicknesses of metal in the bottom of the **U** shaped portion, and the 20 metal displaced by the punch *e*, will form a burr on the under side or lower surface of the **U** shaped joint of the seal which will render it absolutely impossible to separate the joined 25 portions thereof and again place them in the same position while the car is *en route* to its destination. The seal thus effectually secured in position on the car, can only be removed therefrom by cutting, breaking or oth-

erwise mutilating it which would show that 30 the car had been opened.

Having thus fully described my invention, what I claim as new, and desire to secure by Letters Patent, is—

1. A car seal consisting of a strip of metal 35 bulging in width in its longitudinal center to receive its consecutive tag number and having turned over lips near one end forming a loop for the reception of the other end of the strip to form a joint, said joint portion being 40 bent in a **U** shaped form to lock the parts together, as and for the purpose set forth.

2. A car seal consisting of a strip of metal having, near one end turned over lips for the 45 reception of the other end of the strip to form a joint, said joined portions being bent in a **U** shaped form and having a hole punched through the different layers of metal at the bottom of the **U** shaped portion to burr the under side thereof, whereby the joined portions are securely locked together, as and for the purpose set forth.

In testimony whereof I affix my signature in presence of two witnesses.

FRANK ALDRICH.
